Inventor:

UNITED STATES PATENT OFFICE.

JOHN J. PENHALLEGON, OF MINERAL POINT, WISCONSIN, ASSIGNOR TO THE PEN-HALLEGGON COMPANY, OF ST. PAUL, MINNESOTA, A CORPORATION OF SOUTH DAKOTA.

RADIATOR.

1,247,572.

Specification of Letters Patent. Patented Nov. 20, 1917.

Continuation of application Serial No. 76,674, filed February 7, 1916. This application filed April 24, 1917. Serial No. 164,151.

To all whom it may concern:

Be it known that I, JOHN J. PENHALLEGON, a citizen of the United States, residing at Mineral Point, in the county of Iowa and State of Wisconsin, have invented certain new and useful Improvements in Radiators, of which the following is a specification, reference being had therein to the accompanying drawing.

10 This invention relates to improvements in radiators, the present application being filed to take the place of and as a continuation of an application filed by me February 7, 1916, Serial No. 76,674.

15 It is the practice in the art to which the invention relates to employ in connection with the radiator proper or core a separate outside casing that may be properly painted and finished, to the end that, as compared 20 to directly painting the core, the painted or finished surface may be removed from the intimate influence of the heat created by the radiator in action, and thereby preserved.

25 The object of the present invention is to provide improved means for fastening the radiator together with a separate outside shell or casing, to the frame of a motor vehicle that will permit of the quick assembling and removal of the parts for the purpose of renewal, cleaning, or repair, the improved construction being adapted to provide for the ready disconnection and removal of the outer shell or casing from the 30 radiator, and the radiator or core from the 35 vehicle frame.

40 A further object of the invention is to provide for detachably fastening the parts together to obtain a strong, durable construction and to prevent all looseness and play between the parts and rattling incident thereto.

45 A still further object of the invention is to provide an improved construction of the character referred to which will have a finished and ornamental appearance.

50 A particularly important novel characteristic of the invention resides in the provision of an independent positive connection between the radiator proper or core member and the vehicle frame, and the location of said connection at a point near the base or lower portion of the core member and near the horizontal plane of the vehicle framing commonly employed whereby a se-

cure connection and anchorage of the core member to the vehicle frame against movement is obtained and the weight of the core member is supported directly upon the vehicle frame instead of upon the outer casing, the outer casing being thus relieved of all strains incident to supporting the core member, and the employment of a relatively light casing structure being permitted. The special location of the independent connection between the core member and the frame near the base or lower portion of the core member obviates the necessity of employing additional brackets or supports extending upwardly from the vehicle frame. The improved construction permits of the use of a unitary core structure and a unitary casing structure continuous from top to bottom facilitating the assembling and removal of the parts, the outer casing as well as the core member being capable of handling as a whole instead of being each made up of a plurality of separate sections connected together, and the continuous nature of the outer casing being also advantageous as affording a neat and ornamental finish. 80

The invention with other objects and advantages thereof and the particular construction, combination and arrangement of parts comprising the same, will be understood from the following detail description 85 when considered in connection with the accompanying drawings, forming a part hereof and illustrating one embodiment of the invention.

In the drawings:

Figure 1 is a front elevation showing a 90 radiator and casing constructed and connected with an automobile in accordance with the present invention;

Fig. 2 is a side elevation with parts shown in section;

Fig. 3 is a front elevation with parts shown in section;

Fig. 4 is a detail perspective of the radiator proper or core;

Fig. 5 is a detail perspective view of the outside shell or casing, and

Fig. 6 is a detail perspective view of one of the parts of the vehicle frame.

In the drawings, I have illustrated by way 105 of example, a preferred embodiment of the invention but it will be understood that minor changes in and variations of the spe-

cific embodiment of the invention shown, as will appeal to those skilled in the art may be made without departing from the spirit of the invention.

- 5 Referring to the detail description of the drawings wherein like reference characters designate corresponding parts throughout the several views, 1 designates the core or body of the radiator and 2 represents the 10 separate outside shell or casing. The core or body 1 which is shown as a unitary structure is provided near its base or lower portion at opposite sides thereof with outstanding supporting and securing flanges or lugs 1'. 15 These flanges may be provided in any suitable way. In the particular construction illustrated in the drawings; the flanges are provided by angle plates, one member of the plates being brazed, welded, or otherwise 20 suitably secured to the end walls of the core member and the other member of the plates extending horizontally away from the end walls and constituting the flange. The outside shell or casing 2 which is shown as a 25 unitary structure is open at its bottom and adapted to be slipped over the core or body 1. The casing 2 is provided at its lower portion at opposite sides thereof with outstanding securing flanges 2' adapted to be superimposed upon the flanges or lugs 1' of the 30 core or body 1. The core or body 1 and the outside shell or casing 2 are detachably secured to the vehicle frame by bolts 4 or like fastening means, the flanges or lugs 1' of the 35 core or body, the flanges 2' of the outside shell or casing, and the bars 3 of the vehicle frame being provided with suitable openings through which the fastening bolts pass. In the particular construction illustrated in the 40 drawings a transverse supporting frame member 6 is provided having the depressed central portions 6' to receive the base or lower portion of the core or body of the radiator, said frame being turned upwardly 45 as at 7 to engage the end face of the base of the core member, and then turned outwardly as at 7' to afford the horizontal supporting end portions 7' which lie parallel with and to which are secured the flanges 1', 50 2' of the radiator core and outer casing, said end portions 7' being provided with suitable openings for the fastening members 4.

It will be observed that an independent positive connection is provided between the 55 radiator proper or core member and the vehicle frame, a secure connection and anchorage of the core member to the vehicle frame against movement being afforded and the weight of the core or body is supported directly upon the vehicle frame, the outer casing or shell being entirely free from all stress incident to supporting the core member or body. The independent connection of the core member with the vehicle frame 60 is near the base or lower portion of the core

member and near the horizontal plane of the vehicle framing commonly employed, so that the necessity of employing supplemental brackets or supports extending upwardly from the usual framing to support the radiator is entirely avoided. The construction permits of the use of a unitary core structure and a unitary casing structure continuous from top to bottom facilitating the quick assembling and removal of the parts, the 75 outer casing being readily detachable and removable as a whole from the core member or body, and the core member or body readily disconnected from the frame and removable as a unit. 80

The outer casing 2 has the front outer marginal portions 8, 9 and 10, said marginal portions extending in unbroken lines throughout, and the lower marginal portion 10 extending below the supporting and securing flanges 1', 2' of the core member 1 and casing well down in front of the lower front portion of the core and the intermediate depressed portion 7' of the supporting frame part 6 so that these parts are 85 completely concealed from view and a finished and ornamental appearance presented. 90

In order to provide a rigid connection between the core and its outer casing to maintain the same in proper spaced relation and to prevent lost motion and rattling between the parts means on the core member and casing is provided which is adapted to be brought into engagement when the casing is placed over the core and to act to 100 firmly bind the parts together. Said means is shown in the drawing as comprising flanges 12 on the rear face of the core member. The flanges which are shown curved are disposed near the upper part of the 105 core, one at each side thereof and they extend upwardly at an angle to the core face. In sliding the casing downwardly over and upon the core a flange 13 of the casing engages behind the flanges 12 of the 110 core, and is wedged firmly between the core flanges and the adjacent face of the core, the parts being firmly clamped together and held in proper spaced relation. 115

What I claim is:

1. In a device of the character described, the combination with the frame of a motor vehicle, of a radiator core member provided with outstanding flanges at opposite sides and near the lower portion thereof, means 120 for detachably securing the flanges to the vehicle frame, and a removable outer casing for the radiator core member detachably secured in place.

2. In a device of the character described, 125 the combination with a supporting frame part, of a radiator core member provided with outstanding flanges at opposite sides and near the lower portion thereof, a removable outer casing for the core member 130

provided with outstanding flanges at opposite sides and near the lower portion thereof adapted to lie in superimposed relation with the flanges of the core member, and 5 means for detachably securing said flanges of the radiator core member and the flanges of the outer casing to said frame part.

3. In a device of the character described, the combination with the frame of a motor 10 vehicle, of a radiator core member provided with outstanding flanges at opposite sides and near the lower portion thereof, a removable outer casing for the radiator core member provided with outstanding flanges 15 at opposite sides and near the lower portion thereof adapted to occupy a superimposed relationship with respect to the flanges of the core member, and bolts detachably connecting the flanges of the core member and 20 the flanges of the outer casing to the vehicle frame.

4. In a device of the character described, the combination of a radiator core member provided with outstanding flanges at opposite sides and near the lower portion thereof, a removable outer casing for the radiator core member said casing being provided with outstanding flanges at opposite sides and at the lower portion thereof adapted to occupy 25 a superimposed relationship with the flanges of the core member, and a supporting frame part having a depressed central portion adapted to receive therein the lower portion of the radiator core member, and provided with opposite end portions extending above the depressed central portion and parallel with the flanges of the radiator core member and outer casing, and bolts for detachably securing the flanges of the radiator 30 core member and flanges of the outer casing to the end portions of the supporting frame part.

5. In a device of the character described, the combination with a frame of a motor 45 vehicle, of a radiator core member provided with outstanding flanges at opposite sides and near the lower portion thereof, means for detachably securing the flanges to the vehicle frame, and a removable outer casing 50 for the radiator core member detachably secured in place, said outer casing having continuous marginal portions at the top, ends, and bottom, the lower marginal portion extending in front of and concealing the lower 55 part of the radiator core member.

6. In a device of the character described, the combination with a frame of a motor vehicle, of a radiator core member provided with outstanding flanges at opposite 60 sides thereof located at the lower portion thereof a slight distance above the bottom, means for detachably securing the flanges to the vehicle frame, and a removable casing for the radiator core member detachably secured in place, said casing having continu-

ously extending marginal portions at the front thereof, the lower marginal portion extending below the point of location of the flanges of the core member and concealing the lower portion of the core.

7. In a device of the character described, the combination of a radiator core member provided with outstanding flanges at opposite sides and at the lower portion thereof a slight distance above the bottom, a removable outer casing for the radiator core member provided with outstanding flanges at opposite sides and at the lower end thereof adapted to occupy a superimposed relationship with the flanges of the core member, a supporting frame part having a depressed central portion to receive therein the lower portion of the radiator core member and provided with opposite end portions extending above said depressed part parallel with the flanges of the radiator core member and outer casing, and bolts for detachably securing the flanges of the core member and outer casing to the end portions of the supporting frame part, said 80 casing having continuously extending marginal portions at the front, the lower marginal front portion of the casing extending below the flanges of the core member and casing in front of the lower part of the 85 core member and the depressed portion of the supporting frame part, and concealing the same from view.

8. In a device of the character described, the combination of a radiator core member, a removable outer casing for the core member open at its bottom and adapted to be slipped onto the core member, and means on the core member and casing adapted to be brought into engagement as the casing is 90 placed on the core and acting to position the core and casing relative to each other and to secure the same together.

9. In a device of the character described, the combination of a radiator core member, a removable outer casing for the core member open at its bottom part and adapted to be slipped over the core member, one of said parts being provided with a portion having an inclined surface adapted to be 100 brought into engagement with a portion of the other part when the casing is placed on the core and acting to position the core and casing relative to each other and to secure the same together.

10. In a device of the character described, the combination of a radiator core member, a removable outer casing for the core member open at one side to slip over the core member, and flanges on the members 110 adapted to be brought into engagement as the casing is placed on the core member and acting to clamp the casing and core member together.

11. In a device of the character described,

the combination of a radiator core member, a removable outer casing for the core member open at one side to slip over the core member, a flange on one of said parts 5 extending at an inclination to one face thereof, and a flange on the other of said parts, said flanges being adapted to be brought into engagement with each other when the casing is placed on the core member and acting to draw and secure the parts 10 together.

12. In a device of the character described, the combination of a radiator core mem-

ber, an outer removable casing for the core member detachably secured in place, said 15 outer casing being removable in an upward direction from the core member, said core member being provided with marginal flanges which in cross section are obliquely disposed in relation to the core, and flanges 20 on the outer casing section which normally fit between the core flanges and the body of the core.

In testimony whereof I hereunto affix my signature.

JOHN J. PENHALLEGON.
